UNITED STATES PATENT OFFICE.

DENIS SMITH, OF ONTARIO, CALIFORNIA, ASSIGNEE TO HELEN ALISON SMITH, OF BALBOA, CALIFORNIA.

ORCHARD HEATER.

Application filed August 13, 1925. Serial No. 49,968.

This invention relates to orchard heaters and is more particularly directed to an orchard heater in which the fuel is completely burned so as to eliminate smoke commonly formed by such heaters and to obtain a maximum heating value from the fuel employed, and is an improvement over the copending application for orchard heater filed by myself and George A. Smith on March 18, 1925, Serial Number 16,410, patented June 29, 1926, No. 1,590,327.

The principal object of the present invention is to do away with the formation of soot within the heater so as to obtain a more uniform and perfect flow of the fuel into the combustion chamber from the smudge pot or like source of vapors which are burned in the heater.

Other objects and advantages of this invention will be apparent from the following detailed description of a preferred embodiment thereof as illustrated in the accompanying drawings.

In the drawings:

Fig. 1 is side elevation of an orchard heater embodying this invention.

Fig. 2 is a central sectional side elevation thereof.

Fig. 3 is an end elevation taken substantially on the line 3—3, of Fig. 2.

Fig. 4 is a central end elevation of a modified form of heater illustrating a modified type of interior vapor circulating cylinder.

In the preferred embodiment of this invention illustrated in the accompanying drawings, 1 illustrates a smudge pot, which may be of any desired or preferred form, which is connected to the heater 2 through a stack or conduit 3. The vapors formed from the combustion or vaporization of fuel oil, or the like, in the smudge pot 1, is conducted through the conduit 3 to the vapor chamber 4 within the heater 2 where the vapors are circulated over a vapor circulating cylinder 5 through the chamber 6 formed between the outer surface of the vapor circulating cylinder 5 and the inner surface of the heater 2, the vapors circulating out into the combustion chamber 7 of the heater 2 wherein the same are burned and the gases exhausted through a stack 8.

The vapors leaving the conduit 3 into the chamber 6, pass the perforations 9 formed in the shell of the heater 2 so that the said vapors draw air through the perforations 9

into the combustion chamber 7. The vapors and air likewise tend to fill the interior of the vapor circulating cylinder 5 and to burn therein so that the cylinder 5 is heated and soot or carbon is not condensed from the vapors conducted through the conduit 3 on the outer surface of the vapor circulating cylinder 5. By employing such a vapor circulating cylinder 5, I am enabled to greatly increase the heating capacity of the heater 2 by utilizing the combustion space of the chamber 7 and the interior of the vapor circulating cylinder 5 over that type of heater shown in the copending application, Serial Number 16,410, (patented June 29, 1926, No. 1,590,327), above referred to, and the burning of the vapors within the vapor circulating cylinder 5 heats the cylinder 5 and prevents the deposit of soot or carbon upon the exterior surface thereof, thereby assuring complete combustion of the fuel employed.

The heater illustrated in Fig. 4 is exactly similar to the heater illustrated in Figs. 1, 2 and 3, except that the vapor collecting in the cylinder 5^a thereof is formed of crimped 80 corrugated metal so as to provide a number of channels 10^a through which the vapors are conducted in a straight line directly past the perforations 9^a which increases the efficiency of the vapors to draw air through the 85 said perforations 9^a.

Having fully described a preferred embodiment of my invention, it is to be understood that I do not wish to be limited to the exact construction herein set forth, which 90 may, obviously, be varied in detail without departing from the spirit of the invention as set forth in the appended claims.

I claim:

1. In an orchard heater, the combination 95 of an oil vaporizing member, a heater, a conduit connecting the vaporizing member with the heater, a vapor circulating cylinder mounted in the said heater and open at one end, the said conduit being so connected to 100 the heater that the same directs the vapors conducted from the oil vaporizing member perpendicular to the outer periphery of the said cylinder, ports formed in the heater for admitting air to the vapors, and a stack secured to the said heater.

2. In an orchard heater, the combination 110 of an oil vaporizing member, a vapor collecting member, a conduit connecting the vaporizing member with the vapor collect-

ing member, a vapor circulating cylinder mounted in one end of the said vapor collecting member and open at one end, a combustion chamber formed in the vapor collecting chamber in advance of the vapor circulating cylinder, the said conduit being so connected to the said vapor collecting member that the vapors conducted from the vaporizing member are directed perpendicular to the said vapor circulating cylinder,

perforations formed in the vapor collecting member in advance of the vapor circulating cylinder through which air is drawn by the flow of the vapors for combustion with the vapors, and a stack secured to the said vapor collecting chamber near the end opposite the vapor circulating cylinder. ¹⁵

Signed at Ontario, California, this 6th day of August, 1925.

DENIS SMITH.
